United States Patent Office.

JOHN WATTS, OF PHILADELPHIA, PENNSYLVANIA, ASSIGNOR TO
HARVEY & FORD, OF SAME PLACE.

Design No. 4,587, dated January 17, 1871.

DESIGN FOR THE STEM OF A TOBACCO-PIPE.

The Schedule referred to in these Letters Patent and making part of the same.

I, JOHN WATTS, of Philadelphia, county of Philadelphia, State of Pennsylvania, have invented or produced a Design for Stem of a Tobacco-Pipe, of which the following is a specification.

The figure in the accompanying drawing illustrates my design, which consists of a coiled stem, *a*, with a pendent bulb, *b*, one end of the coil being furnished with a socket, *d*, for receiving the projecting portion of the bowl, and the other end being adapted to a mouth-piece.

Irrespective of the bowl, socket *d*, and mouth-piece,

I claim—

The design, consisting of the coiled stem *a*, with its pendent bulb *b*, substantially as described and shown in and by the accompanying drawing.

In testimony whereof I have signed my name to this specification in the presence of two subscribing witnesses.

JOHN WATTS.
